UNITED STATES PATENT OFFICE.

ARVINE N. THOMAS, OF CANTON, OHIO.

FILE-CABINET FOLLOWER.

1,391,595.

Specification of Letters Patent. Patented Sept. 20, 1921.

Application filed December 9, 1920. Serial No. 429,344.

To all whom it may concern:

Be it known that I, ARVINE N. THOMAS, a citizen of the United States, residing at Canton, in the county of Stark and State 5 of Ohio, have invented a new and useful File-Cabinet Follower, of which the following is a specification.

This invention relates to file cabinet followers and more particularly to an adjustable follower adapted to be slidably moved longitudinally within a box or drawer, such as are ordinarily used for filing cabinets for the reception and classification of card indexes, documents, letters or other papers in 10 accordance with systems now generally followed in commercial establishments and offices.

The objects of the invention are the provision of a filing cabinet box or drawer with 20 a slideable adjustable follower adapted to be easily moved longitudinally within the box or drawer and arranged to be automatically locked against rearward movement, the pressure of the papers within the drawer against 25 the lower portion of the follower automatically locking the follower against rearward movement when it is moved into engagement with said papers; while at the same time the follower may be instantly disengaged and moved in a rearward direction 30 to allow changing of the papers within the box or drawer; other objects being the provision of a device of the character mentioned which will be simple and inexpensive 35 in construction and durable and efficient in use and operation.

With these objects in view the invention consists in the construction and arrangement of parts hereinafter described and illustrated in the accompanying drawings, it 40 being understood that various changes in the form, proportion and details of construction may be made without departing from the invention, as defined in the appended claims.

The invention thus set forth in general terms is illustrated in the accompanying drawings, in which—

Figure 1 is a perspective view of a por-

tion of a drawer embodying the invention 50 showing the follower in the locked position.

Fig. 2, a perspective view of a portion of a drawer showing the follower in the unlocked position,

Fig. 3, a transverse view of a portion of a drawer showing a fragmentary portion of a follower therein,

Fig. 4, a fragmentary longitudinal section of a portion of a drawer showing the 60 follower in the locked position therein, the follower being shown in the unlocked position in dot and dash lines, and

Fig. 5, a fragmentary perspective view of a portion of the drawer and follower of a 65 slightly modified form of the invention designed for letter files and similar heavy files, the follower being shown in the locked position.

Similar numerals of reference indicate 70 corresponding parts throughout the several views.

Although the invention may be applied to drawers or boxes of various sizes and proportions, for the purpose of illustration and 75 description the drawer of a document file cabinet of well known character and proportions, is illustrated in Figs. 1 to 4 inclusive.

The drawer may consist of the front 1, 80 the side walls 2, and the bottom 3, formed of a single sheet of metal bent into cross sectional, channel shape as shown and the inverted U-shaped strengthening bar 4 at the rear end thereof. These parts, however, are 85 of usual construction and may be of any ordinary and well known design.

In order to adapt such a drawer for my invention, the outer edges of the side walls 2 have formed thereon the inturned, open, 90 tubular portions 5 which not only strengthen the construction and give a finished appearance thereto, but also act as guides by means of which the follower, indicated generally by the numeral 6, is mounted for longitudinal movement within the drawer.

The under edge of each tubular portion 5 is provided with the spaced rack teeth 7

which act as stops for the follower to hold the same in any desired position as will be further described.

A plate 8 is connected to the rear face of the follower intermediate the upper and lower ends thereof by spot welding or the like and provided with the forwardly extending portions 9, having the inturned flanges 10 at their upper edges, arranged to be received within the open tubular portions 5 of the side walls.

The plate 8 being attached to the follower at a point slightly below the center thereof, the follower will normally rest in the tilted position shown in Fig. 2 and in dot and dash lines in Fig. 4, the upper edge of the plate 8 being out of engagement with the rack teeth 7, thus allowing the follower to be easily moved longitudinally within the 20 drawer.

When papers are placed in the forward end of the drawer in the usual manner and the follower moved forwardly into engagement therewith, the pressure of the papers against the lower portion of the follower will rock the same into the position shown in Fig. 1 and in full lines in Fig. 4, rocking the follower upon the flanged extensions 9 and moving the upper edge of the plate 8 into engagement with the rack teeth 7, automatically locking the follower against rearward movement as it is moved into engagement with the papers.

In order to release the follower to move 35 it rearwardly within the drawer, it is only necessary for the operator to first rock the follower into the position shown in Fig. 2 and in dot and dash lines in Fig. 4, moving the upper edge of the plate 8 out of engagement with the rack teeth 7 in which position the follower may be easily moved rearwardly within the drawer.

It will thus be evident that a follower is provided which is normally in position to be moved longitudinally within the drawer and which will automatically lock against rearward movement upon engagement with the papers filed within the drawer and which may be quickly and easily moved into position to be disengaged from the papers by a rocking movement of the follower, no separate locking device being necessary in order to lock or unlock the follower.

In Fig. 5 is illustrated a slightly modified 55 form of the invention adapted for use upon letter files and other large filing devices in which the parts are formed of heavier material properly strengthened and reinforced.

In this figure each side wall 2^a of the 60 drawer is provided at its upper end with a metal strip 11, spot welded or otherwise attached thereto, the upper portion of which extends over the edge of the drawer and is

bent into rectangular, cross sectional shape forming the guide-way 5^a.

The follower 6^a has connected thereto a plate 8^a provided with the forwardly extending portions 9^a having the out turned flanges 10^a upon their upper edges, the folded back portion 10^b being provided for strengthening these flanges. The rack teeth 7^a are provided upon the lower open edge of the guide portion for engagement with the upper edge of the plate 8^a. The operation of this form of the invention is the same as that above described.

I claim:—

1. In a filing receptacle, longitudinal, tubular guides, a follower within said receptacle, extensions upon said follower extending into said tubular guides, and means adjacent to the tubular guides arranged to be automatically engaged by the follower when the same is moved into engagement with papers in the filing receptacle.

2. In a filing receptacle, longitudinal, tubular guides, each having a longitudinal slot therein, rack teeth formed at one edge of said slot and extensions upon said follower extending into said tubular guides, the follower being normally disengaged from said rack teeth and arranged to automatically engage said rack teeth when moved into engagement with papers in said filing receptacle.

3. In a filing receptacle, longitudinal, tubular guides, each having a longitudinal slot therein, one edge of the wall of said slot having spaced notches therein, a follower within said receptacle and extensions upon said follower extending into said tubular guides, the follower being arranged to be rocked into engagement with said notches to lock the follower against rearward movement.

4. In a filing receptacle, side walls having their upper edges bent inwardly and downwardly, forming open, tubular guides, a follower within said receptacle, extensions upon the follower extending into said tubular guides, the follower being normally disengaged from the rack teeth and arranged to automatically engage said rack teeth when moved into engagement with papers in said filing receptacle.

5. In a filing receptacle, longitudinal slotted guide members, rack teeth formed upon said guide members, a follower within said receptacle, forwardly disposed extensions upon said follower, and flanges upon said extensions extending into said slotted guide members, the follower being arranged to be rocked into engagement with said rack teeth, to lock the follower against rearward movement.

6. In a filing receptacle, longitudinal

tubular guides, rack teeth adjacent thereto, a follower within said receptacle and extensions upon said follower extending into said tubular guides, the follower being normally disengaged from said rack teeth and arranged to automatically engage said rack teeth when moved into engagement with papers in said filing receptacle.

7. In a filing receptacle, longitudinal tubular guides, rack teeth adjacent thereto,

a follower within said receptacle and extensions upon said follower extending into said tubular guides, the follower being normally disengaged from said rack teeth and arranged to be rocked into engagement therewith to lock the follower against forward movement. 15

In testimony that I claim the above, I have hereunto subscribed my name.

ARVINE N. THOMAS.
